DESIGN FOR A COMBINATION CHILD'S VEHICLE AND PARCEL CARRIER

William J. Zepp, Yorktown Village, Md.

Application September 13, 1946, Serial No. 133,297

Term of patent 14 years

(Cl. D14—14)

To all whom it may concern:

Be it known that I, William J. Zepp, a citizen of the United States of America, residing at Yorktown Village, in the county of Montgomery and State of Maryland, have invented a new, original, and ornamental Design for a Combination Child's Vehicle and Parcel Carrier, of which the following is a specification, reference being had to the accompanying drawing, forming a part thereof, wherein:

Fig. 1 is a perspective view of a combination vehicle for children and parcel carrier, showing my new design; and

Fig. 2 is a bottom perspective view thereof, a portion of the handle and the chassis having been broken away for convenience of illustration.

I claim:

The ornamental design for a combination child's vehicle and parcel carrier, substantially as shown.

WILLIAM J. ZEPP.
